UNITED STATES PATENT OFFICE.

GEORGES LÉON EMILE PATAUT, OF PARIS, FRANCE.

DEVICE FOR THE SIMULTANEOUS OBTAINMENT OF THE COMPRESSION AND THE CIRCULATION OF GASEOUS MIXTURES.

Application filed January 14, 1925, Serial No. 2,445, and in France January 17, 1924.

The major part of the processes which are in current use for the obtainment of the synthetic combination of gas under pressure consist in circulating the mixtures of these 5 gases, which have been preliminarily compressed, upon a catalyst which is contained in a reaction chamber. After each passage upon the said catalyst, the portion of the gases which has combined is eliminated from 10 the mixture by dissolving, liquefaction, combination or by other means, whilst the part which has not entered into combination is to be circulated under pressure upon the said catalyst together with a fresh quantity of 15 gas which replaces the amount which has entered into combination and has been therefore eliminated.

The functioning of processes of this kind is attended with serious difficulties—when high 20 pressures must be employed as is the general rule—as concerns the construction of the circulation pumps which must operate upon the maximum pressure both for suction and delivery. It will thus be necessary to employ stuffing boxes which are voluminous and 25 complicated, and in spite of this precaution, leakage cannot be avoided, and this will occasion serious inconveniences and even a certain danger when the gases in circulation 30 are of a noxious character, for instance when they contain ammonia or carbon monoxide. But it has been found according to the present invention that the construction of circulation pumps can be much simplified and 35 the risks of leakage diminished by combining in one apparatus the compressor itself and the circulation pump in such manner that the latter will have but a single joint where it is connected with the last cylinder of the 40 compressor, the latter being supposed to comprise a plurality of cylinders in alignment.

In this manner the gas which tends to escape from the cylinder of the circulation pump through the packing around the piston 45 or piston rod will have no other exit except into the last or high pressure cylinder of the compressor, this cylinder operating at the highest pressure employed in the latter apparatus, or near that of the gas in the 50 circulation pump; so that the leakage will be reduced to a minimum for any given packing arrangement, and the leaking gas will be returned to the circuit and cannot escape into the atmosphere.

The single figure of the drawings append-

ed to the present description shows an example of the said arrangement as applied to a compressor which herein comprises three stages of compression, and the said stages may also represent the last three stages of a 60 compressor having a greater number of stages. It is also supposed that the cylinders are disposed in tandem, (as is the general rule) with the several pistons mounted upon a common piston rod. 65

The gases which are withdrawn through the conduits 1, 1 and enter into contact with both faces of the first piston 2, which operates by double action in the cylinder 3, 3, are discharged through the conduits 4, 4, 70 traverse the cooling device 5, and enter the second cylinder 6, 6, in which they are again compressed by the piston 7; they are then discharged through the conduits 8, 8, traverse the cooling device 9 and enter the third cylinder 10, 10 in which they are compressed by the piston 11 and are discharged through the conduit 12, 12; they may be cooled by the cooling device 13 before entering the reaction chamber 14 in which the gases become 80 partially combined. The combined portion is eliminated in the separating device 15 by any suitable means, for example an outlet (not shown), whilst the uncombined portion proceeds through the conduit 16, 16, to the 85 circulation pump whose cylinder 17 is a restricted extension of the third cylinder 10, 10 of the compressor itself, the piston 18 of said cylinder being formed by the extension of the piston rod 11; the gases are discharged 90 by the piston 18 through the conduit 19 into the pipe 12 preceding the reaction chamber. 95

The cooling device 13—if such is used—may obviously be disposed at 13', forwardly of the junction of the conduit 19 with the conduit 12.

If a plurality of compressors are mounted in parallel, the conduits respectively connecting the different cylinders may be suitably inter-connected, and the same is true 100 for the circulation pumps which may be mounted upon each compressor or upon one or more compressors.

In like manner, the circulation pump, instead of being placed at the end of the compressor, may constitute only the next to the last stage of the same, this being however less advantageous; the important point is that its cylinder shall communicate with the atmosphere, at the joint of its piston or pis- 105 110

ton rod, solely through the medium of the cylinders of the compressor wherein the operating pressure is the highest.

Obviously, the cylinder volume of the circulation pump should have a determined ratio to the volume of the cylinder, taking due account of the amount of the gas which becomes combined during each passage of the same through the reaction chamber. But should it be desired during the course of the operation to vary the amount of gas circulated without any change in the output of the compressor—its speed being thus unaffected—, this may be carried out according to the present invention by disposing between the suction conduit 16 and the discharge conduit 19 of the circulation, a branch circuit 20 whose flow will be regulated by more or less opening the controlling valve 21, and the latter may be either single or double. Inversely, should it be desired to vary the output of the compressor without any change in the amount of the circulation, the plant will comprise, between the suction conduits 1, 1 and the discharge conduits 4, 4, of the first cylinder of the compressor, a branch conduit 22 whose output is regulated by more or less opening the controlling valve 23. This latter branch may obviously be disposed between the suction end of the first cylinder and the delivery conduit of any one of the other cylinders.

What I claim is:

1. A device for effecting the compression and the circulation of gaseous mixtures, comprising a compressor having a plurality of cylinders in series, a circulation pump whereof the cylinder is contiguous to the cylinder of the compressor which operates under the maximum pressure and the piston is secured to the piston of the said compressor, the discharge conduit of the cylinder of the high pressure compressor opening into the discharge conduit of the pump, piping connecting together the suction conduits and the delivery conduits of one of the cylinders of the compressor, and controlling means provided in the said piping whereby the output of the said circulation pump may be varied without any change in the operation of the compressor.

2. A device for effecting the compression and the circulation of gaseous mixtures, comprising a compressor having a plurality of cylinders in series, a circulation pump whereof the cylinder is contiguous to the cylinder of the compressor which operates under the maximum pressure and the piston is secured to the piston of the said compressor, the discharge conduit of the cylinder of the high pressure compressor opening into the discharge conduit of the pump, piping connecting together the suction conduits and the delivery conduits of one of the cylinders of the compressor, and controlling means provided in the said piping whereby the output of the said circulation pump may be varied without any change in the operation of the compressor.

2. A device for effecting the compression and the circulation of gaseous mixtures, comprising a compressor having a plurality of cylinders in series, a circulation pump whereof the cylinder is contiguous to the cylinder of the compressor which operates under the maximum pressure and the piston is secured to the piston of the said compressor, the discharge conduit of the cylinder of the high pressure compressor opening into the discharge conduit of the pump, piping connecting the suction conduits with the delivery conduits of one of the cylinders of the compressor, controlling means provided in the said piping whereby the degree of compression may be varied without any change in the operation of the circulation pump.

3. A device for effecting the compression and the circulation of gaseous mixtures, comprising a compressor having a plurality of cylinders in series, a circulation pump whereof the cylinder is contiguous to the cylinder of the compressor which operates under the maximum pressure and the piston is secured to the piston of the said compressor, the discharge conduit of the cylinder of the high pressure compressor opening into the discharge conduit of the pump, piping connecting together the suction conduits and the delivery conduits of one of the cylinders of the compressor, and controlling means provided in the said piping whereby the degree of compression may be varied without any change in the operation of the circulation pump.

In testimony that I claim the foregoing as my invention, I have signed my name hereto.

GEORGES LÉON EMILE PATART.
